CLAIM

The ornamental design of a tote box, as shown and described.

DESCRIPTION

FIG. 1 is a front elevation of a tote box showing my new design;
FIG. 2 is a top plan view thereof;
FIG. 3 is a rear side elevation thereof;
FIG. 4 is a bottom plan view thereof;
FIG. 5 is a right side elevation thereof;
FIG. 6 is a left side elevation thereof; and
FIG. 7 is a sectional elevation taken along line 7—7 of FIG. 2.

FIG. 1

FIG. 2

FIG. 3

FIG. 4

FIG. 5

FIG. 6

FIG. 7
